FIRE PLACE GRATE.

No. 19,112.

Patented May 28, 1889

FIG. 1.

FIG. 2

UNITED STATES PATENT OFFICE.

EDWARD L. CALEY, OF PHILADELPHIA, PENNSYLVANIA, ASSIGNOR TO
GILBERT COMBS, JOHN BAWDEN, AND JOHN H. BAWDEN, OF FREE-
HOLD, NEW JERSEY.

DESIGN FOR A FIRE-PLACE GRATE.

SPECIFICATION forming part of Design No. 19,112, dated May 28, 1889.

Application filed January 9, 1889. Serial No. 295,885. Term of patent 7 years.

To all whom it may concern:

Be it known that I, EDWARD L. CALEY, a citizen of the United States, and a resident of Philadelphia, Pennsylvania, have invented a new and original Design for a Portable Fire-Place Grate, of which the following is a specification.

My design for a fire-place grate is fully shown in the accompanying photographic illustrations, and the leading feature of the design is the quadrangular basket shape of the grate with the curved sides.

Figure 1 is a perspective view of the grate, and Fig. 2 is a side view of one of the plates.

The design of the front, side, and back plates is of the same general character, and con-

sists of the bottom bars, *a*, and top bars, *b*, on all four sides of the grate, connected by vertical double-ogee-curved bars *d*, with open spaces between the bars. 20

I claim—

The design for a fire-place grate, substantially as described, and as shown in and by the accompanying photographic illustrations.

In testimony whereof I have signed my name 25 to this specification in the presence of two subscribing witnesses.

EDWARD L. CALEY.

Witnesses:

WILLIAM D. CONNER,
HARRY SMITH.
